US00D511205S

(12) **United States Design Patent** (10) Patent No.: **US D511,205 S**
Loberger et al. (45) Date of Patent: **** Nov. 1, 2005**

(54) **LAVATORY**

(75) Inventors: **John M. Loberger**, Germantown, WI (US); **David H. Roland**, Cedarburg, WI (US)

(73) Assignee: **Bradley Fixtures Corporation**, Menomonee Falls, WI (US)

(**) Term: **14 Years**

(21) Appl. No.: **29/225,299**

(22) Filed: **Mar. 14, 2005**

Related U.S. Application Data

(62) Division of application No. 29/209,039, filed on Jul. 9, 2004, which is a division of application No. 29/192,246, filed on Oct. 21, 2003, now Pat. No. Des. 496,450, which is a division of application No. 29/178,393, filed on Mar. 25, 2003, now Pat. No. Des. 484,958, which is a division of application No. 29/158,504, filed on Apr. 4, 2002, now Pat. No. Des. 477,060.

(57) **CLAIM**

We claim the ornamental design for a lavatory, as shown and described.

DESCRIPTION

FIG. 1 is a perspective view of a lavatory deck showing my new design;

FIG. 2 is a front elevation view thereof;

FIG. 3 is a top plan view thereof;

FIG. 4 is a left-side elevation view thereof; and,

FIG. 5 is a right-side elevation view thereof.

The broken lines immediately adjacent to the shaded areas represent the bounds of the claimed design while all other broken lines are for illustrative purposes only; the broken lines form no part of the claimed design.
